M. HERMES

NONREFILLABLE BOTTLE

Filed Nov. 12, 1926

Inventor
Maryanne Hermes

By Clarence A. O'Brien

Attorney

UNITED STATES PATENT OFFICE.

MARYANNE HERMES, OF FAIRMOUNT, NORTH DAKOTA.

NONREFILLABLE BOTTLE.

Application filed November 12, 1926. Serial No. 148,010.

This invention relates to new and useful improvements in non-refillable bottles and has for its primary object to provide a bottle that is equipped internally with the member similar in shape to the cross sectional shape of the bottle and having a snug fit within the bottle, means being provided between the interior of the bottle and said member to permit the same to slide toward the neck of the bottle when the contents thereof is being emptied, but to prevent the return of the member when the bottle is stood upon its end.

By reason of an invention of this character it would be impossible for any one to force the plate member downwardly to the bottom of the bottle after the same has moved to any extent whatever from the bottom so that obviously the bottle could not be conveniently refilled and even though it were filled, the purchaser thereof could readily note the position of the plate member and determine the fact that the bottle contains the original or a substitute content.

One of the main objects of the invention is to provide a non-refillable bottle of this character that is of simple construction and that will operate for the purposes intended under varying conditions.

Other objects will become apparent as the nature of the invention is better understood, the same comprising the novel form, combination, and arrangement of parts herein-after more fully described, shown in the accompanying drawing and claimed.

In the drawing wherein like reference characters indicate corresponding parts throughout the several views:

Figure 1 is a view partly in side elevation and partly in vertical cross section of the invention as applied to a flat type bottle.

Figure 2 is a transverse section thereof.

Figure 3 is a view similar to Figure 1 disclosing the invention applied to a rounded bottle, and

Figure 4 is a transverse section thereof.

First having reference to Figures 1 and 2, 5 designates a generally conventional design of flat sided bottle formed at one end with the usual neck 6. In carrying out my invention the inner surface of one side wall of the bottle 5 is formed with inwardly projecting spaced lugs 7, the lower sides of which are of tapering formation from the

inner surface of the bottle to the outer ends of said lugs as clearly indicated in Figure 1.

Disposed within the bottle is a plate member 8 preferably of the same material of which the bottle is composed and being of a shape similar to that of the cross sectional area of the bottle. This plate 8 is of such dimension as to permit the same to slide vertically within the bottle and to tilt to a very minor degree within the bottle as indicated by the dotted full lines in Figure 1, but yet so as to prevent the plate from being turned within the bottle.

At the edge of the plate 8 adjacent the end wall formed with the teeth 7 there is provided a vertical slot 9 within which the teeth 7 project so as to permit the plate to move past the teeth in an obvious manner.

It will at once be appreciated that the initial position of the plate 8 is within the lower end of the bottle so that the bottle may be properly filled. However, when the bottle is tilted so as to remove the contents therefrom, the plate 8 will automatically move toward the neck of the bottle, this action being permitted by the tapered under side of the lugs 7. However, after the bottle is turned over, the plate 8 will by its own action become slightly tilted within the bottle so that the same will rest at one end upon one of the lugs 7 and accordingly be prevented from moving further downwardly within the bottle.

In the form of the invention disclosed in Figures 3 and 4, the bottle 5' is of rounded configuration and is provided at its inner surface with spaced vertically extending lugs 7' similar to the lugs 7 in the form of the invention shown in Figures 1 and 2. In this instance the plate 8' is of circular formation and the same is also formed at its edge with a notch 9' to permit the movement of the same over said lugs. The operation of this type of bottle is identical with that previously described and a specific description thereof is not believed necessary.

In view of the foregoing description when considered in conjunction with the accompanying claims it will be readily appreciated that I have provided a highly novel, simple, efficient, and inexpensive nonrefillable bottle that is well adapted for all the purposes heretofore designated, and even though I have herein shown and described

the invention as consisting of certain detail structural elements it is nevertheless to be understood that some changes may be made therein without affecting the spirit and scope of the appended claims.

Having thus described the invention, what I claim as new and desire to secure by Letters Patent is—

1. In combination with a bottle, a plate-
10 like member arranged horizontally within the bottle and being of a shape similar to the cross sectional shape of the bottle, said plate adapted for slidable and slightly tilt-
able movement, the plate being adapted to
15 move toward the neck of the bottle when the contents thereof is being emptied, and cooperating means between the plate and the inner wall of the bottle to prevent the movement of the plate in a reverse direction.
- 20 2. In combination with a bottle, a plate-

like member arranged horizontally within the bottle and being of a shape similar to the cross sectional shape of the bottle, said plate adapted for slidable and slightly tilt-
able movement, the plate being adapted to 25 move toward the neck of the bottle when the contents thereof is being emptied, and co-
operating means between the plate and the inner wall of the bottle to prevent the move-
ment of the plate in a reverse direction, said 30 means comprising a series of vertically spaced teeth formed on the inner wall of the bottle, the teeth being tapered at their under side, the plate adjacent the teeth being formed with a slot in its edge, within which 35 said teeth project, the inner edge of the slot engaging the upper face of one of the teeth when the bottle is set in an upright position.

In testimony whereof I affix my signature.

MARYANNE HERMES.
